SNOWPLOW ATTACHMENT FOR MOTOR TRUCKS

Carl H. Frink, Clayton, N. Y.

Application October 20, 1930. Serial No. 489,983

REISSUED

1 Claim. (Cl. 37—44)

This invention relates to a snow-plow attachment for motor trucks of the class set forth in my Patent No. 1,589,748, issued June 22, 1926, in that it comprises a main frame having releasable means for rigidly securing it to the front end of the truck to extend forwardly therefrom, and a supplemental plow-supporting frame adjustably suspended from the main frame for vertical movement relatively thereto.

10 The main object is to increase the efficiency and durability of an apparatus of this character so that it may be driven at a higher speed over country and city roads than has heretofore been practiced and thereby to maintain the roads in 15 a passable condition, at all times, free from snow and ice, at a greatly reduced cost.

One of the specific objects is to bring the entire attachment into sufficiently close relation to the front end of the truck frame to prevent 20 excessive vibration of its various parts and at the same time to cause the rear ends of the mould-boards of the plow to extend some distance beyond and at opposite sides of the front end of the truck-frame for increased strength 25 durability and efficiency, and for shorter turning radius.

Another specific object is converge the mold-boards forwardly at equal angles to the longitudinal center of the truck so as to meet in the 30 vertical plane of the center line with their upper portions forming an acute angle and thereby to reduce the resistance incidental to the forward movement of the plow through the snow and ice and permit the machine to be 35 driven forwardly at a sufficiently high rate of speed to assure the deflection of the snow and ice beyond opposite sides of the roadway.

A further object is to enable the plow-supporting frame with the plow thereon to be conveniently and expeditiously raised and lowered and also tilted forwardly and rearwardly and transversely as may be required when the apparatus 40 is traveling free or when adjusting the plow to the contour of the road bed to regulate the depth of cut.

Another object is to provide the plow-supporting frame with fulcrum-shoes adapted to ride along and upon the road surface and arranged 50 so as to take approximately the entire weight of and load upon the plow and frame and also to form fulcrum bearings upon the roadbed about which the frame and plow may be tilted to regulate the depth of the cut.

55 Other objects and uses relating to specific

parts of the apparatus will be brought out in the following description.

In the drawings:

Figure 1 is a top plan of a plow attachment embodying the various features of my invention 60 as applied to a motor truck, a part of which is shown by dotted lines.

Figure 2 is a longitudinal vertical sectional view of the same apparatus taken in the plane of line 2—2, Figure 1.

Figure 3 is an enlarged vertical sectional view 65 taken in the plane of line 3—3, Figure 1, the outer portions of the moldboards being broken away.

Figure 4 is a horizontal detail sectional view, 70 partly broken away, taken in the plane of line 4—4, Figure 2.

Figure 5 is an enlarged detail sectional view taken in the plane of line 5—5, Figure 4.

Figure 6 is a perspective view of a modified 75 form of plow-point omitting the draft lug shown in Figures 1 and 2, but indicating in dotted lines, the positions of said lug.

As illustrated, this attachment comprises a main supporting frame —1— having lower and 80 upper cross bars —2— and —3— adapted to be rigidly secured to the front end of the chassis frame —a— of a motor vehicle —A—, shown by dotted lines in Figures 1 and 2.

The cross bars —2— and —3— preferably 85 consist of angle irons arranged in vertically spaced parallel relation, the lower bar —2— being secured by rearwardly projecting braces —4— to the underside of the chassis frame —a—, as shown in Figure 1, for transmitting motion 90 to the frame —1— as the truck is moved forwardly.

The cross bar —3— is bolted or otherwise secured to the front end of the frame —a— in a plane above the cross bar —2— for additionally holding the frame —1— in fixed relation to the chassis frame —a—, it being understood 95 that the devices for securing the bars —2— and —3— to the chassis frame —a— are releasable to allow the frame —1— to be attached to and removed from the truck, when desired.

The horizontal cross bars —2— and —3— extend equal distances beyond the longitudinal center of the chassis and are connected near 105 their ends by relatively short upright bars —5—, preferably consisting of angle irons riveted or otherwise permanently secured to the adjacent portions of the cross bars —2— and —3—, equal distances from the longitudinal center of the 110

machine, as shown more clearly in Figures 2 and 3.

A pair of similar upright frame bars —6— are bolted, riveted or otherwise permanently secured 5 at their lower ends to the front faces of the cross bars —3— and to the upper ends of the frame bars —5— to extend upwardly equal distances therefrom in transversely spaced parallel relation and at equal distances from the longitudinal 10 center of the machine, the upper ends of the upright bars —6— being connected by rearwardly and downwardly extending braces —7— having their lower ends bolted or otherwise secured to the chassis frame —a—, as shown more clearly 15 in Figure 1, for holding the upright bars or posts —6— against forward and rearward vibration.

The upper ends of the upright posts —6— are connected by a cross bar —8— bolted or otherwise 20 rigidly secured thereto and extended laterally relatively short distances beyond the same to form suitable anchorages for the flexible 25 cables which support the rear end of the plow-supporting frame hereinafter described, said cross bar —8— preferably consisting of an angle iron arranged with its open angle facing forwardly as shown more clearly in Figures 2 and 3.

The upright bars —6— and upper cross bar —8— are connected by diagonal braces —9— 30 bolted or otherwise secured thereto for stiffening the adjacent portions of the main supporting frame.

A relatively short lengthwise bar —10— is bolted or otherwise rigidly secured to the upper cross bar —8— midway between its ends to extend forwardly therefrom and has its forward end connected by braces —11— to the upright posts —6— some distance below the upper ends thereof for additionally stiffening the upper portion of the main frame and, together with the upright posts —6— and forwardly projecting bar —10—, constitute what may be termed a crane for receiving a plow-hoisting mechanism hereinafter described, the bar —10— being arranged in the vertical plane of the longitudinal center of the chassis.

The arm —10— is connected just back of its front end to the opposite ends of the upper cross bar —8— by diagonal braces —12— to additionally stiffen the arm —10— against lateral vibration, see Figure 1.

Plow-supporting frame

The plow-supporting frame is separate from the main supporting frame for vertical movement relatively thereto and comprises a lower horizontal cross bar —13— extending transversely of the machine equal distances to opposite sides thereof and some distance beyond the lower portion of the main frame, said cross bar —13— being arranged some distance in front of but parallel with the lower cross bar —2— for receiving and supporting a pair of relatively short upright posts —14—.

These posts —14— are bolted or otherwise secured to the bar —13— equal distances from the longitudinal center of the chassis to extend upwardly equal distances therefrom in transversely spaced parallel relation and are connected at their upper ends by a cross bar —15— which is bolted or otherwise rigidly secured to the posts —14— in vertically spaced parallel relation to the lower bar —13—, said posts —14— being connected intermediate their ends by an additional cross bar —16— which is bolted or

otherwise secured thereto to stiffen the adjacent portion of the plow-supporting frame.

The upper bar —15— extends laterally equal distances beyond the posts —14— and has its outer ends bolted or otherwise rigidly secured to an additional pair of upright posts —17—.

The lower ends of the posts —17— are bolted or otherwise rigidly secured to the lower horizontal bar —13— to extend upwardly equal distances therefrom in transversely spaced parallel relation some distance above the upper bar —15—, said posts —17— being arranged at the outer sides of the adjacent posts —14— in spaced relation thereto to permit the passage of suitable thrust bars, presently described, through the intervening spaces.

These upright posts —17— are provided at their upper ends with outwardly projecting laterally extending arms —18— of equal length, bolted or otherwise rigidly secured to their respective posts —17— to project outwardly therefrom at right angles thereto and having their outer ends connected by braces —19— to the upper cross bar —15— of the plow-supporting frame, said braces —19— being extended downwardly and inwardly across the rear faces of the upright posts —17— and having their intermediate portions bolted or otherwise rigidly secured thereto to assist in stiffening the adjacent portions of the plow-supporting frame. See Figure 3.

The outer ends of the lower bar —13— of the plow-supporting frame are provided with similar upwardly divergent brace bars —20— bolted or otherwise rigidly secured thereto and, together with the upper horizontal bars —18— constitute rigid supports for a pair of oppositely arranged forwardly convergent moldboards —21— of the plow for supporting said moldboards equal distances from and at opposite sides of the longitudinal center of the truck chassis.

That is, each moldboard is provided on its inner rear side with a transversely extending rib or flange —22— to which the outer ends of the upper horizontal bars —18— and also the braces —19— are bolted or otherwise rigidly secured as shown more clearly in Figure 3, said bars —18— being secured to the reinforcing ribs or flanges —22— near the upper edges of the moldboards.

These reinforcing ribs —22— extend from points near the upper edges of the moldboards —21— downwardly to points near the lower edges thereof as shown in Figure 2 and are permanently secured to the inner rear faces of the moldboards to assist in maintaining the concavo-convex contour thereof, the lower edges of the reinforcing ribs being flattened and bolted, or otherwise secured, to the adjacent portions of the moldboards.

Additional reinforcing members —23— are bolted or otherwise permanently secured to the inner rear faces of the lower edge of the moldboards, as shown in Figure 3, and are provided with downwardly projecting flanges —23— having anchorages —24— for receiving the lower ends of a pair of chains or cables —25— which are attached at their upper ends to suitable anchorages —26— on the outer ends of the upper bar —8— of the main-supporting frame, as shown more clearly in Figure 3.

The upper ends of the brace bars —20— are bolted or otherwise rigidly secured to the reinforcing members —23— and corresponding portions of the moldboards —21— to additionally

hold the moldboards in equally spaced relation at opposite sides of the longitudinal center of the chassis.

As previously intimated, the moldboards 5 —21— are concavo-convex in cross section and arranged with their concave sides facing forwardly and their front ends meeting in the vertical plane of the longitudinal center of the truck where they are bolted or otherwise rigidly 10 secured to each other to form the vertically concaved cutting vertex of the plow as shown more clearly in Figures 1 and 2.

That is, the meeting ends of the moldboards are provided with forwardly projecting flanges 15 —27— which are bolted or otherwise rigidly secured to each other to assist in holding the moldboards in fixed relation and at the proper angle to each other. See Figure 2.

The lower front edges of the moldboards 20 —21— are disposed at an obtuse angle to each other and are provided with cutting plates —28— of hardened steel or equivalent material riveted or otherwise permanently secured to the adjacent portions of the moldboards, the lower 25 edges of said cutting plates being disposed in a substantially horizontal plane for engagement with the snow and ice adjacent the roadbed.

The remaining portions of the moldboards at 30 the rear of the cutting plates —28— are curved upwardly, rearwardly and forwardly and have their upper longitudinal edges bent inwardly to form reinforcing flanges —29— for stiffening the same, said flanged upper edges of the moldboards being preferably disposed at an acute 35 angle to each other to reduce to a minimum the resistance incidental to the contact of the snow and ice therewith as the machine is propelled forwardly.

Under this construction and arrangement of 40 the moldboards of the plow and resultant reduction of the resistance to its forward movement through the snow and ice, it is evident that the machine may be driven at a relatively high rate of speed under which the snow and 45 ice would be rapidly deflected beyond the sides of the road or some distance beyond the path of travel of the machine.

The lower edges of the moldboards at the rear 50 of the cutting plates —28— are provided with reinforcing bars —30—, preferably angle irons, bolted or otherwise rigidly secured thereto, as shown more clearly in Figures 2 and 3.

In like manner the lower horizontal front edges of the moldboards are reinforced by additional angle bars —30—, welded or otherwise 55 rigidly secured to the inner rear faces thereof in planes slightly above the lower edges of the cutter plates —28— which are also welded or otherwise secured to the lower front faces of 60 the adjacent portions of the moldboards and their reinforcing bars —30—.

The lower portion of the plow-supporting frame is also provided with a pair of bars —31— arranged in transversely spaced parallel relation equal distances from, and at opposite sides of, the longitudinal center of the truck and having their rear ends rigidly secured by any suitable fastening means to the cross bar —13— and their front ends rigidly secured to the reinforcing bars —30—, as shown more clearly in Figures 2 and 4, for supporting the front portion of the plow while the upright posts —17— serve to support the rear portions of the moldboards —21—.

75 The moldboards of the plow may be addition-

ally braced from the bars —31— by brace bars —31'— shown in part in Figure 1.

The plow-supporting frame is connected to the main frame —1— by means of a pair of thrust bars or links —32— arranged in transversely spaced parallel relation at equal distances from the longitudinal center of the truck to extend forwardly and rearwardly between the corresponding posts —14— and —17—, said thrust bars being pivoted at —33— to the lower 80 ends of the upright posts —5— of the main supporting frame —1— and having their front ends pivoted at —34— to the lower bars —31— of the plow-supporting frame, as shown more clearly in Figures 2 and 4, thus permitting the 85 plow-supporting frame with the plow thereon to be adjusted vertically relatively to the main frame —1—.

That is, the rear portion of the plow-supporting frame and corresponding portions of the 90 plow may be adjusted vertically through the medium of the chains or cables —25— by simply engaging different links on the upper ends of the chains in the grab-hook anchors —26— on opposite ends of the upper bar —8— of the 100 main-supporting frame —1—.

The front end of the plow-supporting frame and corresponding portions of the plow may be adjusted vertically by means of a chain or cable —35— having its upper end divided into 105 branches —35'— which are passed over a pair of sprocket wheels —36— on a rotary shaft —37—, the latter being journaled in a suitable gear case —38— on the front end of the upper lengthwise bar —10— of the plow-supporting frame as 110 shown in Figures 1 and 2, said gear case containing a quantity of oil for lubricating the gearing.

The lower end of the hoisting chain or cable 115 —35— is attached to an anchor plate —39— which is rigidly secured to the lower front reinforcing bars —30— just at the rear of the plow point, the point of attachment of the chain —35— to the anchor plate —39— being some distance in front of the pivotal connections 120 —34— between the thrust bars —32— and reinforcing bars —30—, as shown more clearly in Figures 1 and 2.

The lower bars —31— of the plow-supporting frame, are provided with fulcrum shoes —40— 125 welded or otherwise rigidly secured to the undersides thereof intermediate their ends and parallel therewith to ride along and upon the surface of the roadbed as the machine is propelled forwardly.

These fulcrum shoes —40— are located just at the rear of the pivotal connections —34— between the thrust bars —32— and bars —31— of the plow-supporting frame to allow said plow-supporting frame to tilt vertically to different 130 angles about the fulcrum bearings of the shoes —40— upon the roadbed for varying the depth of cut of the cutting plates —28—.

It will now be observed that the plow-supporting frame has a three point suspension from 140 the main supporting frame —1— through the medium of the rear chains —25— and front chain —35— and that the entire plow-supporting frame may be adjusted vertically or tilted to different angles longitudinally by proper adjustment of these chains.

The sprocket wheels —36— and shaft —37— constitute what may be termed a winch adapted to be driven by any suitable gears within the housing —38—, one of said gears being actu- 150

ated by an operating shaft —41— extending rearwardly from the gear case —38— into the cab, as —a'—, of the truck where it is provided with a hand wheel —42— for rotating the same 5 in reverse directions and thereby effecting a corresponding reverse movement of the sprocket wheels —36— for winding and unwinding the front chain —37— thereon and therefrom, to effect the raising and lowering of the front end 10 of the plow-supporting frame.

If desired, the space between the upper edges of the moldboards —21— adjacent the plow point may be covered by a deflecting plate —43—, the purpose of which is to forwardly 15 deflect snow or ice which may be carried upwardly to the top of the plow point and thus prevent such snow and ice from passing rearwardly into the top of the truck.

A relatively thin cutter plate of hardened 20 steel or equivalent material —44— is rigidly secured to the apex of the plow to project forwardly and downwardly therefrom for cutting and breaking up any snow, crust or ice in the path of the plow as the truck is propelled forwardly.

The point of the plow is also provided with a bearing plate —45— of hardened steel or equivalent material rigidly secured thereto to project downwardly and forwardly therefrom between the adjacent ends of the cutting plates —28— and, if desired, may be provided with a forwardly projecting lug —46— having an aperture —47— for attachment to another truck in case it should be necessary to use additional 30 power for the propulsion of the snow plow through excessive quantities of snow and ice.

Operation

Assuming that the plow-supporting frame 40 with the plow thereon has been raised clear of the pavement or ground so that the machine may be propelled from one locality to the place of use, this vertical movement being effected entirely by the proper adjustment of the chains —25— and —35— on the main supporting frame.

When it is desired to use the plow for clearing the roadbed of snow and ice, the chains —25— and —35— will be slackened until the fulcrum shoes —40— contact with the pavement 50 and, in actual practice, these chains will be adjusted so as to allow the plow-supporting frame with the plow thereon to assume a slight upwardly and forwardly inclined position, as shown by dotted lines in Figure 2, when the fulcrum shoes are first brought into contact with the pavement, under which conditions the cutter plates —28— would be more or less clear of the pavement and the front cable —35— would be under more or less tension.

60 Now, if it should be desired to bring the cutter bars —28— into closer relation to the pavement, it would be simply necessary to release the cables —35— by turning the shaft —41— in the proper

direction, and to take up the rear chains —25—, thereby causing the front portion of the plow-supporting frame to rock downwardly about the fulcrum bearing of the shoes —40— upon the pavement, it being understood that this forward and downward tilting movement would be permitted by the slackening of the front chains —35—.

It will be noted that when the plow-supporting frame is lowered sufficiently to allow the shoes —40— to rest upon the pavement, said frame will be more or less balanced forwardly and rearwardly by the fulcrum bearings which allows the plow-supporting frame with the plow thereon to be easily tilted vertically about the fulcrum bearings through the medium of the chains —25— and —35— for regulating the depth of cut of the cutting blades —28— of the snow-plow.

That is, by slackening the chains —25— and tightening the chain —35— the nose of the plow may be tilted upwardly to reduce the depth of the cut, or, when the chains are once adjusted to produce the desired depth of cut and it is necessary to cease further operations of the 100 plow, the entire plow-supporting frame with the plow thereon may be easily and quickly raised clear from the pavement by simply winding the upper ends of the chain —35— upon the sprockets —36— by the proper rotation of the operating 105 shaft —41—, it being understood that this raising and lowering of the plow-supporting frame is permitted by the link connections —32— between the plow-supporting frame and main frame —1—.

110 It will be evident from the foregoing description and the drawings that the construction is particularly simple, durable and efficient for the work required and that the various moving parts may be easily and quickly set or adjusted to the 115 various positions best adapted for the work, but obviously various changes may be made in certain details of the construction without departing from the spirit of the invention.

What I claim is:—

In a snow-plow attachment for motor trucks, a main frame and means for rigidly securing it to the front end of the truck, in combination with thrust bars hinged to the frame and projecting forwardly therefrom for vertical swinging movement, a second frame hinged intermediate its front and rear ends to the front ends of the thrust bars for vertical rocking movement and provided at the rear of its hinge with road-engaging fulcrua, a plow carried by the second frame, and means mounted on the main frame and connected to the second frame in front of its fulcrua for tilting the second frame vertically about the fulcrua bearing on the road and thereby varying the depth of cut of the 135 plow.

CARL H. FRINK.
